BOLLARD LIGHT FIXTURE

Marvin Paul Friedberg, New York, N.Y., assignor to
Bajer Industries Incorporated, Fairfield, N.J.

Filed June 6, 1974, Ser. No. 476,880

Term of patent 14 years

Int. Cl. D10—06; D26—03

U.S. Cl. D48—31

FIG. 1

FIG. 2

FIG. 3

FIG. 1 is a top plan view of a bollard light fixture showing my new design;

FIG. 2 is a side elevational view of the light fixture shown in FIG. 1; and

FIG. 3 is another side elevational view of the light fixture of FIGS. 1 and 2, taken from a viewpoint that is about 90° laterally to the point of view from which this fixture is observed for the FIG. 2 showing.

I claim:

The ornamental design for a bollard light fixture, substantially as shown and described.
